UNITED STATES PATENT OFFICE.

JAMES W. JOHNSON, OF NEW BRUNSWICK, NEW JERSEY, ASSIGNOR TO JOHNSON & JOHNSON, OF NEW BRUNSWICK, NEW JERSEY, A CORPORATION OF NEW JERSEY.

COLLAPSIBLE TUBE.

1,100,433.

Specification of Letters Patent. Patented June 16, 1914.

Application filed February 4, 1913. Serial No. 746,142.

To all whom it may concern:

Be it known that I, JAMES W. JOHNSON, a citizen of the United States, and a resident of New Brunswick, in the county of Middlesex and State of New Jersey, have invented a new and useful Collapsible Tube, of which the following is a specification.

This invention relates to collapsible metal tubes, such as paint tubes, or tubes for containing and dispensing dentifrice, shaving cream, and the like.

One of the principal objects is to insure the tube reaching the consumer in the form of an air-tight original package. To this end I provide a puncturable hermetic seal protected by a screw cap that is equipped with a spur or piercing point for puncturing or breaking said seal, and with a threaded wall or skirt that protects the point and also acts as a guide and feed for the same.

The nature, characteristic features, and scope of the invention will more readily be understood from the following description taken in connection with the accompanying drawing, forming a part hereof, wherein—

Figure 1, is a perspective view of a tube embodying features of my invention; and Figs. 2 and 3, are sectional views, illustrating, respectively, the relative arrangement of the parts prior to and in the act of destroying the seal.

The neck 1, of the filled tube has its orifice or dispensing end 2, closed by a thin film 3, of metal, for example, soft solder. To protect the seal formed thereby and also

to provide for destroying the same, a double-ended cap 4, is employed, both ends of which are internally threaded so as to take the threads 5, of the tube.

As shown in Figs. 2 and 3, the cap is in the form of an internally threaded tube having a division wall or partition 6. The latter is formed or provided with an axial or endwise directed spur or point 7, which does not extend beyond its surrounding wall 45 or skirt. It is evident that by reversing the cap and screwing it upon the neck of the tube the point will impinge and destroy the metal seal, as clearly to be seen in Fig. 3.

Eventually either end of the cap may constitute a closure for the tube.

Having described the nature and object of the invention, I claim:—

A collapsible tube having its dispensing end or orifice sealed by a thin film of metal, 55 and having screw threads, and a double ended cap whereof both ends are internally threaded so as to take the threads of the tube, said cap having a medial part or division wall provided with a fixed endwise directed piercing member adapted when the cap is screwed on the tube to pierce and destroy the seal and plug the orifice.

In testimony whereof I have hereunto signed my name in the presence of two sub- 65 scribing witnesses.

JAMES W. JOHNSON.
